Albert G. Beckrow

BY

Albert G. Beckrow

ATTORNEY

UNITED STATES PATENT OFFICE.

ALBERT G. BECKROW, OF SAGINAW, MICHIGAN.

DESIGN FOR A BICYCLE-STAND.

SPECIFICATION forming part of Design No. 28,754, dated May 31, 1898.

Application filed January 8, 1898. Serial No. 685,886. Term of patent 3½ years.

To all whom it may concern:

Be it known that I, ALBERT G. BECKROW, a citizen of the United States, and a resident of the city and county of Saginaw, State of Michigan, have invented and produced a new and original Design for Bicycle-Stands, of which the following is a specification, reference being had to the accompanying drawings, forming a part thereof.

Figure 1 is a front elevation of the design. Fig. 2 is a side view of same.

As shown, the leading and material features of the design consist of the base A, standards B, and the figure of a barrel or keg,

supported by and between the standards, the 15 keg C having at its lower edge notches cut to receive the wheel of a bicycle.

Having thus described my invention, what I claim as new, and desire to secure by Letters Patent, is—

The design for a bicycle-stand as shown and described.

In testimony whereof I hereunto set my hand this 3d day of January, 1898.

ALBERT G. BECKROW.

In presence of—

A. H. SWARTHOUT,
JOHN McCAFFERY.
